(57) **CLAIM**

The ornamental design for a bottle opener ring, as shown and described.

DESCRIPTION

A portion of the material in this patent document is subject to copyright protection under the copyright laws of the United States and of other countries. The owner of the copyright rights has no objection to the facsimile reproduction by anyone of the patent document or the patent disclosure, as it appears in the United States Patent and Trademark Office publicly available file or records, but otherwise reserves all copyright rights whatsoever. The copyright owner does not hereby waive any of its rights to have this patent document maintained in secrecy, including without limitation its rights pursuant to 37 C.F.R. §1.14.

FIG. 1 is a front, bottom, left side perspective view of a bottle opener ring, showing our new design.

FIG. 2 is a rear elevation view of the ring design shown in FIG. 1.

FIG. 3 is a right side elevation view of the ring design shown in FIG. 1, the left side elevation view being a mirror image thereof.

FIG. 4 is a bottom plan view of the ring design shown in FIG. 1.

FIG. 5 is a top plan view of the ring design shown in FIG. 1; and,

FIG. 6 is a front view of the face of the ring design shown in FIG. 1.
